[57] CLAIM

The ornamental design for a toy building carrying case, substantially as shown and described.

DESCRIPTION

FIG. 1 is an elevational view of one side of a toy building carrying case showing our new design;

FIG. 2 is an elevational view taken from the right side of FIG. 1;

FIG. 3 is an elevational view taken from the opposite side of FIG. 1; and

FIG. 4 is an elevational view taken from the left side of FIG. 1;

FIG. 5 is a top plan view of the design of FIG. 1; and

FIG. 6 is a bottom plan view of the design of FIG. 1.
